UNITED STATES PATENT OFFICE

JAMES H. WAGENHORST, OF JACKSON, MICHIGAN

ARC LAMP

Application filed July 23, 1928. Serial No. 294,678.

My invention relates to improvements in arc lamps.

The principal object of my invention is to provide an arc lamp which is simpler and more compact in structure than any similar lamp heretofore known or used. A further object of my invention is to provide an improved arc lamp which may be manufactured more economically due to the simplicity of its construction and the reduction in the number of parts. Another object of my invention is to provide an arc lamp structure which is more compact than those heretofore known and in which it is easier to take out the carbons and substitute new ones. A further object of my invention is to provide an arc lamp which will give a uniform light output and operate efficiently in any position and, to that end, one of my objects is to provide an operating mechanism for the arc lamp which reduces friction between the parts to the minimum.

A further object of my invention is to provide an arc lamp in which the electrodes and the operating parts therefor are all mounted upon or supported from a single bar which constitutes, as it were, the backbone of the structure. A further object of my invention is to provide a clutch cooperating with one of the electrodes and a clutch-operating link which are connected by levers to the supporting frame, so that the movement of the clutch-operating link will be limited to a definite path regardless of the position of the lamp in use. A further object of my invention is to provide a construction in which compactness is secured and, at the same time, the clutch-operating link is so connected with the operating lever and the clutch as to give the required leverage between such parts. A further object of my invention is to provide an operating solenoid having a core provided with guiding means so that the core will be confined to movement in a right line regardless of the operating position of the lamp, thus avoiding undue friction which otherwise might result when the lamp is used in certain positions.

Further objects, and objects relating to details and economies of construction and op-

eration, will definitely appear from the detailed description to follow. In one instance, I accomplish the objects of my invention by the devices and means set forth in the following specification. My invention is clearly defined and pointed out in the appended claims. A structure constituting a preferred embodiment of my invention is illustrated in the accompanying drawings, forming a part of this specification, in which:

Figure 1 is a view, in side elevation, of an arc lamp embodying my invention;

Fig. 2 is a view of the lamp in front elevation;

Fig. 3 is a top plan view of the lamp.

Fig. 4 is a view of the frame, the electrodes and the operating mechanism therefor, the cabinet having been removed;

Fig. 5 is a view in front elevation of the parts shown in Fig. 4;

Fig. 6 is a top plan view of the parts shown in Figs. 4 and 5;

Fig. 7 is a horizontal, sectional view taken on the line 7—7 of Fig. 4, showing the clutch and its mounting;

Fig. 8 is a vertical, sectional view taken on the line 8—8 of Fig. 7;

Fig. 9 is a vertical, sectional view through the dash pot;

Fig. 10 is a detail, sectional view taken on the line 10—10 of Fig. 4, showing the holder for the upper electrodes and

Fig. 11 is a detail, sectional view taken on the line 11—11 of Fig. 4, showing the mounting for the lower electrodes.

In the drawings, the same reference numerals refer to the same parts throughout the several views and the sectional views are taken looking in the direction of the arrows at the ends of the section lines.

In general, I accomplish the objects of my invention by providing a supporting frame consisting of a bar having its upper and lower ends turned forwardly. The lower electrode, or electrodes, are supported from the forwardly-turned lower end of this bar. The clutch-operating lever and the dash pot are supported from the forwardly-turned upper end of the bar. The operating solenoid

is also supported from the bar, which thus constitutes the backbone of the arc lamp structure. I have simplified the construction and reduced the number of parts by eliminating the customary guide for the upper electrodes and providing a clutch cooperating with one of them, which is supported by a rocker arm and has connected thereto a clutch-operating link, the upper end of which is connected to the operating lever. The upper electrode, therefore, is supported by a parallel linkage and is compelled to move in the same path regardless of the operating position of the lamp. This has proved very effective in eliminating sources of friction, besides reducing the number of parts. I have succeeded in making the structure very compact, while providing the necessary leverage, by bending in opposite directions the upper and lower ends of the clutch-operating rod and connecting them to the clutch and the operating lever, respectively.

In order to eliminate a considerable source of friction, I have provided a guide for the lower end of the solenoid core which prevents its rubbing against the solenoid, or other parts of the lamp structure, when the lamp is tilted. I have also provided a dash pot of the compression type which is mounted on the forwardly turned upper end of the supporting bar and in which a plunger works, said plunger being connected by a link to the clutch.

In the drawings, I have illustrated a lamp of the single arc type having, however, two pairs of carbons so mounted and arranged that the arc will transfer automatically from one pair to the other, thus giving twice as long a period of operation before it becomes necessary to trim or replace the carbons. My invention, of course, could be embodied in a lamp structure employing only a single pair of carbons or could be embodied in a structure having a twin arc instead of a single arc.

Referring to the numbered parts of the drawings, in which I have illustrated an arc lamp constituting one embodiment of my invention, I have shown a supporting frame consisting of the bar 10 having its upper and lower ends turned forwardly, at 11 and 12, respectively. A slot 13 is formed in the end 12 of the bar. A post 14, positioned in the rear end of this slot, is surrounded by an insulating sleeve 15, and clamped in the slot 13 by bolts 16 and nut 17, as shown in detail in Fig. 11. The upper end of post 14 is fastened by a rivet 22 to the rear clamping member 18 for clamping the lower electrodes.

The lower carbon electrodes 20 and 21 are supported in parallel relationship by the clamping members 18 and 19, each provided with the alined concave portions 23 and 24, which embrace the lower ends of the carbons. These clamping members are held together by the clamping screws 25, one of which may

serve as a terminal to which one of the line wires supplying current for the arc lamp is connected.

The upper carbon electrodes, 26 and 27, are clamped in parallel relationship by the clamping members 28 and 29, having alined concave portions embracing the upper ends of said electrodes and forming the holder for the upper electrodes. These members are clamped together upon the upper ends of the electrodes by the clamping screws 30 and 31, the screw 31 serving as a terminal for the lead 91. A guide bracket 32 is fastened to the clamping member 29 by screw 34, and is surrounded by insulation 33 so that the guide bracket is insulated from the clamping members and the electrodes. The upper end of this bracket is turned laterally, at 35, and has a hole therein through which the clutch-operating rod 36 extends.

The clutch-operating lever is pivoted at the end of the forwardly-extending portion 11 of the main supporting bar. This clutch-operating lever is of U-shape comprising the side members 37 with their rear ends bent laterally away from each other, at 38, and the base member 39. The upper end of the clutch-operating rod is bent forwardly, at 44, and pivotally connected to the forward end of the lever 37, which straddles it. This connection is best seen in Fig. 6. A bolt 40 extends through the legs 37 of the operating lever and through an insulating sleeve 45, fixed in an eye 43 formed at the forward end of the arm 44.

Nuts 41 are screwed on the bolts 40 on either side of the eye 43, and insulating washers 42 are interposed between said nuts and the eye 43. In this way, the upper end of the clutch-operating rod is insulated from the operating lever but pivotally connected thereto. The operating lever straddles the front end of the portion 11 of the supporting bar, and it is pivotally connected thereto by means of cotter pin 46, as shown in Fig. 5.

The lower end of the clutch-operating rod 36 is bent rearwardly, at 47, and pivotally connected to the clutch member by the cotter pin 48. The clutch member comprises a strap bent to form the two rearwardly-extending portions 49 and 50 spaced from each other and connected by the portion 51. The arm 47 of the operating rod lies between the spaced portions 49 and 50 of the clutch, as shown in Figs. 7 and 8. The forward end of the portion 49 of the clutch is bent laterally, at 52, and then bent, at 53, to embrace one of the carbons, as shown, the carbon 26. The other member 50 of the clutch is bent laterally, at 54, and then bent at 55 so as to loosely surround the other carbon 27. This clutch member is supported by a rocker arm 56, the forward end of which is bent laterally, at 57, and extends through the forward portions of clutch arms 50 and 49, being held in place

with respect thereto by cotter pins 57' (see Fig. 7). This portion 57 of the rocker arm extends just beneath the forward end of the arm 47 of the clutch-operating rod, so as to act as a stop for the rod under certain conditions. The rear end of the rocker arm 56 is bent laterally, at 58, and the portion 58 is journaled in a sleeve 59, which is surrounded by an insulating sleeve 60 and mounted in a bracket 61, fastened by bolts 62 to the main supporting bar 10.

A cross-pin 63 extends through the end of the portion 58 of the rocker arm and this cross-pin works in a slot 64, which limits its movement and, thereby, limits the rocking movement of the rocker arm 56.

A dash pot 65 is fastened to the upper arm 11 of the main supporting bar. The dash pot is provided with a stem 66 extending upwardly from the closed upper end. This stem extends through the arm 11 and has nuts 67 and 68 threaded thereon, on opposite side of the arm, so as to hold the dash pot fixed in position relative thereto, while permitting its adjustment. A plunger 69 works in the dash pot 65, and has a central opening in which is fixed a sleeve 70, the lower end of which is connected by a cotter pin 71 to the upper end of a rod 72. The lower end of the rod 72 is bent laterally at 73 and extends through clutch arms 50 and 49, being secured in place relative thereto by the cotter pin 74. Movement of the clutch member, therefore, causes a movement of the plunger 69 within the dash pot. This dash pot is of the compression type. It tends to retard upward movement of the plunger 69, within the dash pot, due to the compression of the air therein and the limited vent provided for the escape of such air, but it permits free downward movement of the plunger. To this end, a valve 75 is provided closing the upper end of the tube 70, and having a stem 76 within said tube which carries a cotter pin 77 extending through slots 78 formed in the walls of the tube. This permits a limited movement of the valve stem with reference to the tube, such as is necessary to unseat the valve upon the downward movement of the plunger 69.

The clutch-operating solenoid 80 is mounted upon the supporting arm 10, being carried by upper and lower brackets 81, fastened by bolts 82 to the bar 10. A core 83 works with the solenoid 80. A guide rod 84 is pivotally connected, at 85, to the lower end of this core, and is slidably mounted in a hole 86 formed in a bracket 87, fastened to the bar 10. This furnishes a guide for the core so that the core will not rub against the solenoid and thus cause friction when the lamp is used in a tilted position. Springs 88 are connected to the upper end of the core 83 and these springs are connected, at 89, to the flaring rear ends 38 of the operating lever.

One line wire 90 is connected to the upper end of the solenoid 80. The current comes in through the wire 90, passes through the solenoid 80, and, thence, through the lead 91 to the upper electrodes. The current passes through one or the other of the upper electrodes to the corresponding lower electrode and, thence, through the clamping members for the lower electrodes and the terminal screw to the outgoing lead 92. Of course, it will be understood that suitable resistance may be included in this circuit as may be necessary to provide the proper voltage and amperage for efficient operation.

The lamp and the operating mechanism are housed within a cabinet having an elongated upper part, 93, and an enlarged lower portion 94, which is of substantially parabolic form. A handle 95 is pivoted to the side walls of the upper portion 93 of the cabinet, as shown in Figs. 1 and 2. The front of the upper portion of the cabinet is closed by a removable plate 96 provided with a plurality of perforations 104, through which air can get into the upper part of the cabinet for the purpose of cooling the operating mechanism. The plate 96 is provided with an edge-groove 97 which fits over the flange at the front edge of the portion 93 of the cabinet, so that, this front plate can be removed by sliding it upwardly on the front of the cabinet. A reflector 98 is mounted within the lower portion 94 of the cabinet. This reflector consists of a flat sheet of metal, so polished as to form an adequate reflector, and it is carried by the clutch member. Holes 101 are formed in this reflector plate to permit the upper carbons 26, 27 to pass therethrough. A tongue 99 is struck up from the reflector, at the points where the holes are formed to admit the carbons, and this tongue 99 is fastened to the portions 52, 54 of the clutch by the screws 100. This reflector, therefore, is carried by the clutch and is movable with it as the latter rises and falls in the operation of the lamp. The mounting of this reflector upon the clutch assists in making the structure more compact than would otherwise be the case.

It will be observed that this lamp structure is a very simple and compact one. The supporting bar constitutes a very simple frame and one which can be cheaply manufactured, and the operating mechanism is so mounted on this supporting bar that the whole lamp is very compactly arranged. It will be noted that no guide plate is provided for the movable electrodes, as has been the practice heretofore, and that the clutch is so mounted on a rocker arm as to dispense with the use of such a guide member. This arrangement of the clutch mounted on a rocker arm and cooperating with the movable electrodes is a novel one, which contributes to the simplicity of the structure and its economical manufacture. Referring to Figs. 7 and 8 it

will be seen that, when the circuit is closed through the solenoid, the clutch-operating rod will be lifted and this tilts the clutch member around the end 57 of the rocker arm 5 so that the clutch will grip the electrode and left the same as the clutch-operating rod moves upward. It will hold it in this position until the circuit through the solenoid is broken due to the extinguishment of the arc 10 as the carbons burn away. When this happens, the clutch-operating rod will descend, tilting the clutch in the reverse direction and lowering it until it frees the electrode and permits the latter to move downwardly with 15 respect to the clutch when the lower end of the clutch-operating rod hits the portion 57 of the rocker arm, which acts as a stop. It will also be noted that the stop pin 63 serves to limit the pivotal movement of the rocker 20 arm about its journal. This makes a very simple, cheap and effective construction of clutch.

It will also be noted that a compact arrangement is secured, while, at the same time, sufficient leverage is given, by bending in opposite directions the upper and lower ends of the clutch-operating rod to their points of connection with the lever and the clutch respectively. Furthermore, the parts are so 25 mounted that friction is reduced very greatly due to the fact that the clutch-operating rod and, hence, the carbons are suspended by a parallel linkage arrangement consisting of the rocker arm 56 and the operating lever 30 37. The carbons will always move in the same path regardless of the position of the lamp when in use. This is very important as it prevents friction due to the binding of the carbons with stationary parts of the lamp 35 and it makes a lamp structure which operates 40 to give a uniform light output regardless of the position in which it is used. I find this particularly important in designing a lamp to be used for medical treatments, which must 45 frequently be operated in a tilted position. Similarly, the guide bracket for the solenoid core eliminates another source of friction when the lamp is used in a tilted position.

The cabinet and its mounting is very simple and cheap and by providing a reflector 50 mounted on the clutch I have saved somewhat in the necessary space. The carbons may be very readily removed, when it is necessary to replace or trim them, the upper carbons being removable through the holes 103 55 provided in the top of the portion 93 of the cabinet. It will be seen that there is nothing in the way to prevent the slipping of these carbons out through the upper openings. 60 Similarly, the lower carbons may be removed through the openings 102 in the base of the portion 94 of the cabinet.

I am aware that the particular embodiment illustrated herein may be changed considerably, without departing from the spirit 65

of my invention, and, therefore, I claim my invention broadly as indicated by the appended claims.

What I claim is:

1. An arc lamp comprising the combination of a supporting bar, a lower electrode holder supported by the lower end of said bar, an operating lever pivoted on the upper end of said bar, a clutch-operating rod suspended from one end of said lever, an upper electrode holder, upper and lower electrodes secured to said holders, a rocker arm pivotally mounted on said bar, a clutch pivotally connected to said rocker arm and the lower end of the operating rod and cooperating 70 with the upper electrode, a solenoid supported by said bar and a core cooperating 75 with said solenoid and connected to said operating lever.

2. An arc lamp comprising the combination of a supporting bar having its upper and lower ends turned forwardly, a lower electrode holder supported by the forwardly-turned lower end of said bar, an operating lever pivoted on the forwardly-turned 80 upper end of said bar, a clutch-operating rod suspended from one end of said lever, an upper electrode holder, upper and lower electrodes secured to said holders, a rocker arm pivotally mounted on said bar, a clutch 85 pivotally connected to said rocker arm and said rod and cooperating with the upper electrode, a solenoid supported by said bar and a core cooperating with said solenoid and connected to said operating lever. 90

3. An arc lamp comprising the combination of a supporting bar having its upper and lower ends turned forwardly, a lower electrode holder supported by the forwardly-turned lower end of said bar, an operating lever pivoted on the forwardly-turned 95 upper end of said bar, a clutch-operating rod suspended from one end of said lever, an upper electrode holder, upper and lower electrodes secured to said holders, a rocker arm pivotally mounted on said bar, a clutch pivotally connected to the lower end of the operating rod and to said rocker arm and cooperating 100 with the upper electrode, a solenoid supported by said bar, a core cooperating 105 with said solenoid and connected to said operating lever, a dash pot carried by the forwardly-turned upper end of said bar and a plunger connected to said clutch and working 110 in said dash pot. 110

4. In an arc lamp, the combination of a frame, a rocker arm journaled on said frame, a plurality of cooperating electrodes, a clutch cooperating with one of said electrodes and directly carried by said rocker arm, a clutch-operating link directly connected to said clutch, a solenoid, a core for said solenoid, and operating connections between said core and link. 125

5. In an arc lamp, the combination of a 120

- frame, a rocker arm journaled on said frame, means for limiting the rocking movement of said arm, a plurality of cooperating electrodes, a clutch cooperating with one of said electrodes and directly carried by said rocker arm, a clutch-operating link directly connected to said clutch, a solenoid, a core cooperating with said solenoid and operating connections between said core and link.

5 6. In an arc lamp, the combination of a frame, a rocker arm journaled on said frame, means for insulating said rocker arm from said frame, means for limiting the rocking movement of said arm, a plurality of cooperating electrodes, a clutch cooperating with one of said electrodes and directly carried by said rocker arm, a clutch-operating link directly connected to said clutch, a solenoid, a core for said solenoid and operating connections between said core and link.

10 7. In an arc lamp, the combination of a frame, a sleeve surrounded by insulating material, a bracket secured to said frame and supporting said sleeve, a rocker arm having one end bent to form a trunnion journaled in said sleeve, a cross pin carried by said trunnion and cooperating with a slot in the end of said sleeve to limit the movement of said arm, a plurality of cooperating electrodes, a clutch cooperating with one of said electrodes and carried by said rocker arm, a clutch-operating link connected to said clutch, a solenoid, a core for said solenoid and operating connections between said core and link.

15 8. In an arc lamp, the combination of a frame, a rocker arm journaled on said frame, a plurality of cooperating electrodes, a clutch having a rearwardly extending arm and a portion embracing one of said electrodes, said clutch being carried by the end of said rocker arm, a clutch-operating link connected to the rear end of said clutch arm, a solenoid, a core for said solenoid and operating connections between said core and link.

20 9. In an arc lamp, the combination of a frame, a plurality of cooperating electrodes, a clutch member having a portion embracing one of said electrodes and a rearwardly extending arm, a rocker arm journaled on said frame and having a laterally-extended trunnion at its forward end on which said clutch is pivoted, a clutch-operating link connected to said clutch arm, a solenoid, a core for said solenoid and operating connections between said core and link.

25 10. In an arc lamp, the combination of a frame, a plurality of cooperating electrodes, a clutch having a portion embracing one of said electrodes and a rearwardly-extending clutch arm, a rocker arm journaled on said frame, on which said clutch is pivoted, a clutch-operating rod having a rearwardly-extending lower end pivotally connected with the rear end of said clutch arm, a solenoid, a core for said solenoid and operating connections between said core and said clutch-operating rod.

30 11. In an arc lamp, the combination of a frame, a plurality of cooperating electrodes, a clutch having a portion embracing one of said electrodes and a rearwardly-extending clutch arm, a rocker arm journaled on said frame, and having a laterally-extending trunnion at its forward end on which said clutch is pivoted, a clutch-operating rod having a rearwardly-extending lower end pivotally connected to the rear end of said clutch arm, a solenoid, a core for said solenoid and operating connections between said core and said clutch-operating rod.

35 12. In an arc lamp, the combination of a frame, a plurality of cooperating electrodes, a clutch cooperating with one of said electrodes and having a rearwardly-extending clutch arm, an operating link having a rearwardly-extending arm at its lower end pivotally connected to the rear end of said clutch arm, a clutch-operating lever pivotally connected to said frame, the forward end of said lever being pivotally connected to a forwardly-extending arm at the upper end of said link, a solenoid, a core for said solenoid and operating connections between said core and lever.

40 13. In an arc lamp, the combination of a supporting bar having its upper end bent forwardly, a plurality of cooperating electrodes, a clutch cooperating with one of said electrodes, a clutch-operating link having its lower end connected to said clutch, a U-shaped clutch-operating lever straddling the forwardly-extending portion of said bar and pivoted thereon, the upper end of said link having a forwardly-extending arm disposed between the legs of said U-shaped lever and pivotally connected thereto, means for insulating said link from said lever, a solenoid and a core for said solenoid operatively connected with said lever.

45 14. In an arc lamp, the combination of a supporting bar having a forwardly turned lower end provided with a slot therein, a post clamped in said slot and insulated from said bar, an electrode and a pair of clamping members clamped about said post and electrode.

50 15. In an arc lamp, the combination of supporting means, a plurality of electrodes, a clutch cooperating with one of said electrodes, means for actuating said clutch, and a reflector connected to and movable with said clutch.
